COMBINED SOCKET AND REFLECTOR

John Weritz, Cicero, Ill.

Application September 11, 1935, Serial No. 40,183

4 Claims. (Cl. 240—6)

The invention relates to electric light fixtures, and particularly to lamp socket structures for confined situations, and to lamp sockets for use in connection with reflector devices which closely embrace the lamp, to the end that lamps may 5 be removed from confined situations with ease, safety, and despatch.

It is a particular aim of the invention to combine the function of a swinging socket and switch 10 to the end that in moving a light or socket to position for removal or insertion of the lamp, the socket will be disconnected from the lighting circuit and risk of shock or injury obviated.

An important object of the invention is to 15 improve the construction of such an appliance to the end that construction of a novel kind will be presented, which may be manufactured with a minimum of expense for material and operations, and wherein the mounting of the appliance in wiring jobs may be carried out by the 20 ordinary workman with a minimum of labor, and with a minimum requirement for mounting and attaching fixtures of special or other kinds.

A novel feature of invention lies in means for 25 holding the movable socket yieldingly in normal operative position but freely movable manually to inoperative position, where the lamp may be removed, or it may receive a new lamp.

Additional objects, advantages and features 30 of invention lie in the construction, arrangement, and combination of parts involved in the embodiment of the invention, as will appear from the following description and accompanying drawings disclosing one of the possible embodiments 35 of the invention, and wherein

Figure 1 is a front view of a two-light unit embodying my invention.

Figure 2 is a longitudinal section thereof on the line 2—2 of Figure 1.

Figure 3 is a side elevation of the unit with the reflector in section and part of one socket in section.

Figure 4 is a side elevation of the complete unit.

Figure 5 is a section on the line 5—5 of Figure 3.

Figure 6 is a cross section on the line 6—6 of Figure 2.

Figure 7 is a similar view on the line 7—7 of Figure 3.

Figure 8 is an inner elevation of one of the socket members detached.

There is illustrated a trough-like reflector body 10, which at the same time constitutes a casing for the two-lamp unit shown. One lamp receptacle only may be incorporated if desired. This

casing-reflector is stamped in one piece from sheet metal, being U-shaped in cross section throughout its length, and the ends comprising integral semi-circular continuations of the sides. The bottom is curved for proper reflection and 5 the edge is provided with an outturned flange 11 adapted to serve as a stop and support in mounting the fixture. Midway of the length of the casing a mounting block 12 of insulating material is secured to the bottom of the casing. The 10 body portion of the block is a narrow, longitudinally extending wall, longitudinally disposed and affording a space on each side thereof within the casing to accommodate wires and terminal parts mounted on the block at each side. The outer 15 or top longitudinal face of the block lies inwardly of the plane of the flange 11 slightly. The block may be moulded of any suitable plastic, such as porcelain, or otherwise formed. Secured to opposite sides of the wall 13 there are sheet metal contact and framing plates 14 and 15 insulated from each other, the plate 15 being formed with a contact flange 15' at each end, both bent at right angles across the opposite ends of the block, being set in channels formed on the ends of the 20 wall 13 to receive them. In this way there is provided a portion of insulation outwardly of 25 and flush with the flange 15'. These contact faces so formed, have an aperture therethrough near the outer or top edge of the wall 13. The 30 metal of the plate 14 is cut away at the medial part next the outer longitudinal edge of the block, to permit mounting of switch and receptacle members to be secured to the block. Each plate is held by screws engaged through the wall 13 35 from the opposite side, the screw heads being countersunk. The plate 15 has material removed to a greater depth.

Two lamp-and-switch receptacles 16 are provided, which may be of identical form, if desired, and consist of an insulating body preferably of a moulded plastic having a socket in the outer end, the wall around this being circular except at the outer side where it is extended slightly and flattened in a plane parallel to that 40 of the flange 10, thus providing a broadened face 45 of the flange 10, thus providing a broadened face with flat sides. The socket 17 in the outer end of each receptacle is of a size to set in the casing at one end outwardly of the block 12 on the proper axis of focus of the reflecting surfaces, and 50 set in each socket there is the usual threaded receptacle sleeve 18 of metal. The head or inner end of the sleeve is open and flanged at the 55 sides next the bottom of the socket as at 19, as is familiar. The material removed from the

opening of the inner end of the sleeve end is retained in integral jointure with the sleeve and bent longitudinally from the sleeve forming a flat lug 20 so that it may project through a corresponding slot 20' in the inner end or head of the socket. Either as a continuation of this or joined thereto as shown, there is a switch blade and retaining member 21, which if applied may be of thicker metal, and is offset a little, so that it cannot 5 be drawn outward through the slot. Within the opening in the head of the sleeve there is a fixed center contact 22 of familiar form held by the axial bolt 23. The inner end of the receptacle is formed with a recess 24 opposite the 10 socket, and spaced from the lug 20 and blade, in which there is set snugly the base of a switch arm 25, bent over its base and normally bearing against the contact flange 15'. The switch arm is formed with a nodule 26 adapted to engage 15 yieldingly in the aperture in the flange 15' and serving as a means to prevent the opening of the switch casually. The bolt 23 is extended 20 through the base of the switch arm 25 and receives a nut as shown whereby the arm 25 and 25 contact 22 are held in assembly. An additional slot 27 parallel to the one 20' may be formed through the head of the socket of the receptacle on the opposite side of the axis of the receptacle from the one through which the lug 20 is engaged, though only one slot is used in each 30 receptacle. This permits the receptacle bodies to be used interchangeably, however, as one slot is used at one end of the device and the other slot is used when the receptacle is mounted at 35 the other end of the device.

The body of the receptacle is formed with a plate 28 projected longitudinally from its inner end over the outer side of the wall 13, this plate being flush with and formed as a continuation of 40 the flattened side of the receptacle body. On the inner side of the plate 28 near its extremity a pivot yoke 29 is secured by screws 29' extended from the outer side of the plate 28. The yokes are U-shaped and have ears extending on each 45 side of the wall 13, suitable pivot pins being engaged through the ears and wall 13. The ears on the yokes 29 are long enough to allow the plate 28 to clear the wall 13 sufficiently for the pivotal movement of the receptacle, as desired.

50 Two receptacles are pivoted on the block 12 extending in opposite directions and the pivot pins are likewise sufficiently spaced longitudinally of the wall 13 to permit the necessary swing of the receptacles to clear the casing sufficiently for ready grasping of a lamp screwed into the sleeve 18.

On each receptacle a spring plate 30 is mounted on the outer face of the plate 28, being held under the screws 29', and these plates are projected beyond the extremities of the plates 28 and curved inwardly so as to form leaf springs 31 which bear against and yieldingly oppose each other when either receptacle is swung outward. This is intended to cushion the stoppage of the 65 swinging movement of the receptacles, and minimize liability of breakage of the wall 13. By using material in the plates 30 of the same width as the plate 28, great spring strength may be attained while using comparatively thin stock.

70 Inwardly of the holes in the plate 14 under the blades 21, screws 33 may be engaged through the wall 13 and into the plate 15 to retain the same, while at one end, the screw 33 may also hold a wire binding terminal 34, supplemental fastenings being provided for the latter as required,

a screw 33' being shown. Over the more recessed central upper edge portion of the plate 15 a screw 34' may be engaged through the wall 13, holding a central wire binding terminal 35 and the plate 14 together and against the block 12. Due to the clearances between the wall 13 and sides of the casing 10 insulated wires 36 may be laid in the casing beside the wall 13 and secured in the terminals. 5

Suitable openings may be made medially in 10 the sides of the casing to pass the wires outwardly therethrough, as indicated in Figure 4.

In the assembly of the device the blades 21 are both disposed at the same side of the device, and arranged to engage respective end portions of the plate 14, which is apertured in its upper part where the blades overlap it, and each blade is formed with a nodule to engage the aperture, making for better contact as well as effecting yielding retention of the switch in closed 20 position. The blades 21 stop short of each other sufficiently to enable ready mounting of the wire terminal therebetween. 25

In use, the device being assembled as described, the fixture may be mounted in various confined locations, as, in reading lamps, show window fixtures, show case corners, in drawers, refrigerators, etc. Being secured in place, the receptacles are alternately operated by grasping the sides of the broadened side of the receptacle body and drawing 30 it outwardly from the case 10, to the special or open position, so that the lamp 37 may be inserted. This done, this receptacle is pressed back to normal position and the operation repeated with the other receptacle. As each receptacle is 35 drawn outward, the switch blade 21 moves outward on the plate 14 without clearing it however, while the switch arm rides on the insulation outwardly of the contact flange 15' on the end of the wall 13. At the outermost position the nodule 26 40 will engage outwardly of the angle between the top or outer edge face of the wall 13 and the end face thereof to yieldingly hold the receptacle in open position conveniently for removal of the lamp or replacement thereof. The engagement 45 of the springs 31 will tend to prevent careless operators from abruptly forcing the receptacles outwardly to such limit as to break the porcelain or other insulation material. 50

I claim:—

1. In a fixture of the character described an elongated insulation body, having an end face and an outer face and having a contact set in one, means to form electrical connection therewith, a receptacle pivoted on the body to swing from juxtaposition with one face toward the other, a resilient wiper on the receptacle having movement toward and away from the axis of the pivot and including resilient means to press the wiper on the contact, and a second contact on the body spaced from the first and adjacent said axis, a contact on the receptacle to lie beside the second contact on the body, said two last named contacts including resilient means to bear them together in a direction parallel to said axis, and being of an extent to remain in lapping contact throughout movement of the receptacle, said wiper having a prominence thereon to engage the angularity between the first named two faces to oppose movement of the receptacle on its pivot at certain stages of its movement, and electrical connections for said contacts on the body. 65

2. In a device of the character described, a body base member, two receptacles pivoted thereon for 70 75

movement alternatively from normal positions to open positions in a common direction but extending in opposite directions from their pivots, and having parts convergently movable relatively on 5 operation of either receptacle from normal toward open position, and resilient means interposed between the last named parts for coengagement for the purpose described.

3. In a device of the character described, a body 10 member having an elongated wall projecting therefrom, said wall having end faces and an edge face, a contact in the end faces, means to form electrical connection therewith, a receptacle pivoted on the body adjacent each end face to 15 swing from juxtaposition with respective end faces toward the edge face, a resilient wiper on each receptacle for engagement with respective contacts, a second contact on the wall terminating adjacent the end faces of the wall, a contact blade 20 on each receptacle cooperable with the second contact, the blades being of a length to remain in lapping contact throughout movements of the receptacles, releasable means between respective blades and the contact for holding the receptacles 25 in normal positions, and electrical connections for the second contact.

4. A lighting fixture comprising a trough-like reflector having its side portions cut away for admission of electrical conductors, a body member mounted within the reflector adjacent the cut away portions and including binding posts for attachment of the electrical conductors, a wall on the body member, said wall having end faces and an edge face, a contact in the end faces in electrical connection with one of the electrical conductors, a receptacle pivotally mounted on the body adjacent each end face to swing from juxtaposition with respective end faces toward the edge face, a resilient wiper on each respective receptacle for engagement with respective contacts, a second contact on the wall terminating adjacent the end faces of the wall and in electrical circuit with the other electrical conductor, a contact blade on each receptacle cooperable with the second named contact, the blades being of a length to remain in lapping contact throughout movements of the receptacles, and releasable means between respective blades and the contact for holding the receptacles in normal positions.

JOHN WERITZ. 25
